C. E. GODLEY.

LAMP WITH PIVOTED REFLECTOR.
APPLICATION FILED APR. 26, 1917.

1,236,423.

Patented Aug. 14, 1917.

UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF NEW YORK.

LAMP WITH PIVOTED REFLECTOR.

1,236,423.

Specification of Letters Patent. Patented Aug. 14, 1917.

Application filed April 26, 1917. Serial No. 164,615.

To all whom it may concern:

Be it known that I, CHARLES E. GODLEY, a citizen of the United States, and residing at Detroit, in the county of Wayne and 5 State of Michigan, have invented a new and Improved Lamp with Pivoted Reflector, of which the following is a specification.

This invention relates to means for varying the general direction and the character 10 of the beams of light projected by lamps of the headlight type, by swinging the reflector of the lamp and at the same time moving the source of light toward or from the focal center of the reflector.

15 This invention consists of a lamp body and a reflector pivotally mounted therein, a lamp-bulb and a support therefor slidably mounted in the reflector, means for swinging the reflector on its pivots, and a lever 20 system mounted on the reflector and connected to the lamp body whereby the lamp-bulb support will be slid in or out as the reflector is swung on its pivots. It further 25 consists in adjustably mounting the member connecting this lever mechanism to the body so that the incandescent filament in the lamp-bulb may be moved to the focal center of the reflector. This invention further 30 consists in the details of construction illustrated in the accompanying drawings and particularly pointed out in the claims.

In the accompanying drawing, Figure 1 is a central longitudinal vertical section of this improved lamp. Fig. 2 is a similar section 35 on a larger scale showing the movable mechanism of this lamp in another position. Fig. 3 is a rear elevation of this movable mechanism.

Similar reference characters refer to like 40 parts throughout the several views.

The lamp body 1 shown in the drawings is of any desired construction, but is preferably cup-shaped and provided with a door 45 consisting of the ring 2 and lens 3. An auxiliary ring 4 having a flange 5 at its inner edge is mounted in this body and carries the pivots 6 for the reflector 7. A coupling 8 of any desired type may be mounted in the body 1 and constitutes the connection 50 between the wires 9 and 10.

A sleeve 11 is mounted on the reflector surrounding the rear opening therein and in this sleeve is slidable the tubular connector 12, of well known construction, which re-

ceives the lamp-bulb 13 at its front end and 55 the plug 14 which retains the wire 10 at its rear end. A plate 15 having flanges 16 and 17 and an upturned ear 18 is mounted on this sleeve 11. A wire or cord 19 connects to the flange 17 and passes through the hole 60 20 in the body and by means of this flexible connector the rear end of the reflector is swung down.

The ring 4 carries a pair of small lugs 22 between which the bar 23 is slidable. An up- 65 turned front end 24 of this bar is threaded to receive the screw 25 carried by the ring 4 and by means of this screw the bar can be moved parallel to the axis of the lamp body. The spring 26 connecting to the rear end of 70 this bar and to the flange 16 on the plate 15 pulls this bar rearwardly. A pin 27 is carried by the ear 18 and on this pin a small lever is pivoted. The outer end of the arm 28 of this lever is in the form of a cam that 75 engages an ear 29 on the rear end of the connector 12. A tension spring 30 extends from this ear 29 to the plate 15 to pull the connector forward while a link 32 extends from a pin 33 carried by the arm 34 of the lever 80 to a pin 35 preferably integrally formed on the bar 23. This pin 35 may be slipped into or out of the hole 36 in this link when the link is turned at right angles to the position shown in Fig. 2.

85 When the axis of the reflector coincides with the axis of the lamp body and the lamp is mounted on an automobile, the screw 25 is turned until the lamp-bulb is in proper focus, which will cause the beam of light 90 to be concentrated onto a point in the roadway some distance ahead of the vehicle. A pin 37 holds the reflector in this position.

When the reflector is in the position shown in Fig. 1, the beam of light will be blurred 95 or diffused and thrown down to the road much nearer the vehicle. This latter position is especially useful for city driving as the light is not so intense. The movement of the reflector is limited by the flange 5 on 100 the ring 4.

The position shown in Fig. 1 will probably be that most commonly desired by the majority of drivers, the concentrated light beams being used only occasionally and being obtained by a pull on the wire or cord 19. It is obvious that by turning the lamp upside down the reverse condition would

exist. The details and proportions of the parts may all be varied without departing from the spirit of my invention.

I claim:—

- 5 1. The combination of a lamp body and a reflector pivotally mounted therein, a lamp-bulb and a support therefor slidably in the rear end of the reflector, and a cam mounted on the reflector for moving said bulb in one direction and permitting it to move in the opposite direction as the reflector is swung in one direction or the other on its pivots.
- 10 2. The combination of a lamp body and a reflector pivotally mounted therein, a lamp-bulb and a support therefor slidably in the rear end of the reflector, a cam mounted on the reflector for moving said bulb in one direction and permitting it to move in the opposite direction as the reflector is swung in one direction or the other on its pivots and a spring connected to said bulb support to move it in said opposite direction.
- 15 3. The combination of a lamp body and a reflector pivotally mounted therein, manually operable means to swing the reflector in one direction on its pivot, a spring to swing the reflector in the opposite direction, a lamp bulb and a support therefor movably carried by the reflector, a cam for moving the bulb in one direction as the reflector is swung by said manually operable means and a spring to return the bulb when the reflector is swung back by the spring.
- 20 4. The combination of a lamp body and a reflector pivotally mounted therein, manually operable means to swing the reflector in one direction, a bar connected to said body, a spring connected to said bar and to said reflector to return the same, a lamp bulb and a support therefor slidably mounted in the reflector, a cam mounted on the reflector, a link connected to the cam and to said bar to move the bulb rearwardly when the reflector is swung in one direction, and a spring to return the bulb when the reflector is swung in the opposite direction.
- 25 5. The combination of a lamp body and a reflector pivotally mounted therein, manually operable means to swing the reflector in one direction, a bar connected to said body, a spring connected to said bar and to said reflector to return the same, a lamp bulb and a support therefor slidably mounted in the reflector, a cam mounted on the reflector, a link connected to the cam and to said bar to move the bulb rearwardly when the reflector is swung in one direction, and a spring to return the bulb when the reflector is swung in the opposite direction.

a spring connected to said bar and to said reflector to return the same, a lamp bulb and a support therefor slidably mounted in the reflector, a cam mounted on the reflector, a link connected to the cam and to said bar to move the bulb rearwardly when the reflector is swung in one direction, a spring to return the bulb when the reflector is swung in the opposite direction, and means to adjust the connection between the bar and lamp body to focus said lamp bulb.

6. The combination of a lamp body, a reflector pivotally mounted therein, a connector tube slidable in the rear end of the reflector and having a lateral extension, a lamp-bulb mounted in the front end of the connector, a spring to move the connector and lamp-bulb forward, a lever fulcrumed on the reflector and having a cam at the end of one arm to engage the extension on the connector to force it back, and a link connected to the other arm of the lever to cause it to swing to force the connector rearwardly when the reflector is tipped down.

7. The combination of a lamp body, a reflector pivotally mounted therein, a connector tube slidable in the rear end of the reflector and having a lateral extension, a lamp-bulb mounted in the front end of the connector, a spring to move the connector and lamp-bulb forward, a lever fulcrumed on the reflector and having a cam at the end of one arm to engage the extension on the connector to force it back, a link connected to the other arm of the lever to cause it to swing to force the connector rearwardly when the reflector is tipped down, flexible means to swing down the rear end of the reflector and to force the lamp-bulb rearward, and a spring to restore the reflector to normal position.

8. The combination of a stationary lamp body and a reflector mounted to tilt within the body, a lamp-bulb and a support therefor slidably in the rear end of the reflector, and means mounted on the reflector and connecting to the stationary body for moving the bulb relative to the reflector when the reflector is tilted within the body.

CHARLES E. GODLEY.
